UNITED STATES PATENT OFFICE

2,257,976

VARIABLE PITCH PROPELLER

Charles L. Moorman, Blue Island, Ill.

Application November 2, 1938, Serial No. 238,304

1 Claim. (Cl. 170—162)

This invention relates to improvements in air circulating means for general application and of particular utility in connection with refrigerator cars, an important object being the provision of a variable pitch blower or fan which, in its preferred embodiment, is adapted for unidirectional movement of air regardless of the direction of rotation of the fan structure.

Viewed from another aspect, it is an object of the invention to provide air circulating means of general application and particularly suited for use in refrigerator cars, wherein there is provided a fan having blades mounted on a hub portion for movement to change the pitch of the blades, and means for automatically pivoting the blades in one or another direction depending upon the direction of rotation of the fan structure or hub thereof, together with power take-off means coacting with the wheels of the refrigerator car to drive the fan, the fan blades being pitched in such manner that they will drive air in one direction only, regardless of the direction of rotation of the driving shaft or hub portion thereof, so that it is immaterial in which direction the car moves.

A further and more particular object is the provision of a variable pitch propeller or blower device including a hub having pivoted blades and mechanism operated by movement of the hub in opposite directions to pivot the blades and change their relative pitch or face responsive to reversals in rotation of the hub structure.

Other objects and advantages characterizing the invention reside in certain details of construction, operation, and form of the parts of the illustrative embodiment hereinafter described in view of the annexed drawing, in which:

Fig. 1 is a vertical median section through the length of a refrigerator car;

Fig. 2 is a perspective view of the power take-off mechanism;

Fig. 3 is an enlarged horizontal section through the friction drive wheel in the take-off mechanism shown in Fig. 2;

Fig. 4 is a section through the blower structure;

Fig. 5 is a plan view of the reversing mechanism and hub structure of the blower, seen in the direction of line 5—5 of Fig. 4; while

Fig. 6 is a transverse section along line 6—6 of Fig. 5.

In one of its applications illustrated in Fig. 1, the invention includes a fan or blower 10 mounted at each end of a refrigerator car near the opening 11 leading from the upper region of an ice bunker 12. The fan or blower 10 is of the

preferred construction hereinafter to be described and includes a spindle or drive shaft which is operated through a suitable flexible drive shaft and cable means 13 having driving connection as at 14 (Fig. 2) with the shaft of a friction power take-off wheel 15 arranged for driving engagement with a wheel 16 of a car.

The take-off mechanism may be of the type shown in Fig. 2 or in either of my copending 10 U. S. applications, Serial No. 190,202 or Serial No. 238,305. In the arrangement of Fig. 2, the friction drive wheel 15 is provided with beveled peripheral edge portions 17 which cooperate with the wheel 16 and are especially adapted to remain 15 in driving engagement with the wheel when the trucks are turned on curved track sections. The spindle for the wheel 15 is journaled in the opposite arms 18 and 19 of a trunnion bracket, the arms being joined by a bight portion 20 which 20 lends rigidity to the structure, as does the cross brace 21. The free ends of the trunnion arms, are pivoted on a shaft 22 secured in mounting brackets 23 and 24 which may be supportably attached to the under structure of the car adjacent the wheel 16, as illustrated in Fig. 1. A sleeve 25 is secured to the trunnion arms for movement therewith and has a radial projection 26 which bears against a spring 27 seated at its opposite end on an extension 28 from bracket 23. 25 An operating lever 29 is fulcrumed as at 30 on an attaching bracket 31 also secured to the under structure of the car, the inner end of the lever being pivoted as at 32 to an arm 33 secured to one of the trunnion arms. By grasping 30 the handle portion 34 and moving the lever up and down, the trunnion structure may be raised and lowered relative to the wheel 16 to move the friction wheel 15 into and out of driving engagement therewith. A locking bracket 35 also 35 mounted on the under side of the car, provides slots in which the lever may be disposed to maintain the same in one or another of its pivoted positions. This bracket also is provided with a sealing pin 36 removably mounted in spaced ears 40 45 37 in a position to block shifting of the lever from one slot to another, the pin 36 being apertured at its lower end to receive a seal applied thereto by the trainman.

In the arrangement of Fig. 3, the friction drive 50 wheel is journaled in the trunnion arms by means of a sleeve spindle 40 keyed to the wheel as at 41 and embracing at one of its ends the bearing race 42 and the cooperating bearing ring 43, which is clamped in the chambered portion of 55 a bearing housing 44 by a collar 45 clamped by

set screw means 46 to one end 13a of the flexible driving connection or cable 13, the housing 44 having a threaded nipple 47 screwed into the trunnion arm 18 in a manner to force the collar 45 against the outer bearing race, so that the corresponding end of the spindle sleeve 40 is adequately journaled, the opposite end of the sleeve extending through a bearing race 50 seated in a housing 51 secured in the opposite trunnion arm 19, the sleeve extending into the hub of an auxiliary driving pulley 52 and terminating in a hub collar 53, the sleeve being coupled with the pulley by a key 54. An extremity 55 of the flexible driving shaft is connected for rotation with the sleeve 40 by means of a plug 56 of fluxable metal moulded into the sleeve around the drive shaft, the hub collar 53 being of the split-ring type clamped on the sleeve by a screw 57, similarly to the arrangement 84—86—87 of Fig. 4.

A preferred form of the improved variable pitch fan or blower is illustrated in Fig. 4 and includes a floating hub or inertia member 60 mounted near one end of a spindle sleeve 61 and having a plurality of radially extending pins 62 on which are pivotally mounted blades 63 constituting the air moving means of the blower. The blades are preferably formed of sheet metal turned back upon itself (Fig. 5) and joined at their free edges 64, to provide the trailing edge of the blade, and to leave a hollow portion extending throughout the length of the blade in which the mounting pins 62 are disposed, the blades being journaled on the pins 62 by sleeves 65 and 66 secured in the hollow portion thereof by any suitable means, such as spot welding or the like, and the journals or pivot sleeves 65 being positioned at a point between the trailing edge 64, and the leading edge 67 which corresponds to the bight portion of the folded blade sheet.

Means for automatically pivoting the blades responsive to rotation of the hub in opposite directions includes the provision of a radially extending pin 70 in the bight portion of each blade near the hub 60, the lower ends of these pins projecting into slots 71 in a collar 72 mounted on the sleeve 61 and secured for rotation with the latter by a key 73.

Since the hub 60 floats on the spindle sleeve 61 while the collar 72 is rigid with the sleeve, it will be apparent that rotation of the collar in opposite directions will tend to move the several pins 70 correspondingly with a resultant pivoting of the several blades so that the latter will be pitched in opposite directions relative to the direction of rotation of the hub and collar with the result that the curved leading edge 67 will always be directed to "grab" the air or other fluid for deflection off the trailing edge 64 regardless of which way the fan is rotated.

The relative rotational movement of the floating hub 60 and the collar 72 is controlled by the provision of a stopping pin or finger 72a on the floating hub 60 and which projects in an axial direction into a wide slot 74 in the collar 72, which slot is wider in the direction of rotation than the stopping projection 72a, so that there is a limited freedom of relative rotation between the collar 72 and the hub 60. Thus, when the collar 72 rotates in one direction, the side 74a of the wide slot 74 will move toward and bear against the projection 72a with a consequent pivoting of the blades 63 (Fig. 5), whereas a reverse movement of the collar 72 will cause the opposite side 74b of the slot 74 to move toward and bear

against the projection 72a, which results in pivoting the blades 63 in an opposite direction, as a result of the projection of the pins 70 in the several slots 71 and the relative inertia of the rotatable or floating member 60.

To complete the fan structure, the spindle sleeve 61 is mounted in spaced bearing races 80 (Fig. 4) secured in a covered sleeve 81 which in turn is mounted by means of a set screw 82 on a collar 83 embracing the opposite end portion 13b of the flexible cable 13. The driving extremity 55a of the flexible drive shaft extends into the bore of the sleeve 61 and has its end portion secured in a plug 84 by means such as the pin 85. The plug 84 and the spindle sleeve are joined for rotation together by a split collar 86 (Fig. 5 also), the split sides of which are drawn together by a clamping bolt 87 which has a portion of its shank projected through a slot near the outer end of the sleeve 61 for disposition in a chamfered groove 88 in the plug 84 whereby the plug, the sleeve, and the split ring 86 are all keyed together for rotation by the end portion 55a of the flexible driving shaft. A suitable mounting flange 90 is extended from the housing sleeve 81, whereby the fan structure generally indicated at 10 may be mounted as shown in Fig. 1.

The foregoing construction of the novel fan provides, what is termed for convenience, both a unidirectional and a variable pitch propeller, for it will be evident that the shape and arrangement of the blades as particularly described in conjunction with Figs. 4 and 5, is such that regardless of which direction the blades are moved, the air will always be "grabbed" or seized along the curved edges 67 at the rear of the blades and deflected from the forward edges 64, this arrangement being of particular advantage in the application of the fan in refrigerator cars, since the latter are likely at any time to have their direction of movement changed.

It will be understood that the blades 63 may themselves be pitched relative to coordinates therethrough, and the pivotal movement of the several blades by the automatic means heretofore described will vary the pitch of the propeller depending upon the direction in which the blades are moved.

The objects and advantages of the invention may be realized by other forms of construction than that specifically detailed in the illustrative embodiment, and it will be understood that the invention as defined in the appended claim is intended to include all equivalent forms, modifications, and applications of the illustrative arrangement.

Having thus described my invention, what I claim as new and desire to protect by Letters Patent is:

A fan including a driving shaft, a driving hub member mounted for rotation with said shaft, a driven hub member arranged to float on said shaft, one of said hub members having a slot of predetermined length extending in the direction of rotation thereof and the remaining hub member having a projection extending into said slot and of a breadth less than the length of said slot so as to be movable in opposite rotational directions in the latter whereby to permit limited relative rotational displacement of said hub members and to provide a driving connection between the same for joint rotation thereof, a plurality of pivot members mounted on one of said hub members to extend in a direction at an angle to the axis of rotation thereof, a fan blade pivotally

mounted for adjusting movement on each of said pivot members, each of said blades having an eccentrically positioned finger projected into slot means provided in the remaining hub member whereby relative rotational displacement of said hub members will effect adjusting pivotal movement of said blades in opposite directions, said

hub members being displaced as aforesaid as a result of the inertia of said floating hub member consequent upon a change in the direction of rotation of the same with said driving hub member.

CHARLES L. MOORMAN.
